UNITED STATES PATENT OFFICE.

ABEL E. CHERNACK, OF PROVIDENCE, RHODE ISLAND.

LATHE.

1,168,162.

Specification of Letters Patent.

Patented Jan. 11, 1916.

Application filed September 8, 1915. Serial No. 49,601.

To all whom it may concern:

Be it known that I, ABEL E. CHERNACK, a subject of the Emperor of Russia, and a resident of the city of Providence, county of Providence, and State of Rhode Island, have invented a certain new and Improved Lathe, of which the following is a specification.

My invention relates to lathes and particularly to multiple lathes the object of my invention being to provide a heavy duty lathe for rough turning cylindrical metal pieces several at a time.

In the accompanying drawings, Figure 1 is a side elevation partially broken away of a lathe in which my invention is embodied in one form; Fig. 2 is a partially broken plan thereof; Fig. 3 is a broken end elevation of the same; Fig. 4 is a vertical section 20 through a detail.

The bed 10 of the lathe is of usual construction and has firmly attached thereto a head stock 11. Mounted in the latter is a driving pulley 12 having a long sleeve 13 carrying pinion 14. The latter meshes with gear 15 compounded with pinion 16 which in turn engages with gear 17 fast on the end of shaft 18 at the back of the bed and extending the length of the latter. A key 30 groove 19 (Fig. 3) reaching the length of this shaft receives the keys of the several pinions 20 which are slidably engaged therewith. These pinions 20 in turn mesh with peripheral gear teeth on face plates 21. Through this triple gear system the drive of the pinion 14 is transmitted to any number (here five) of face plates.

The spindle 22 of the headstock extends through the sleeve 13 of the pulley 12 and 40 in the other direction through the sleeve 23 of the adjacent face plate 21. A key connection 24 between this sleeve 23 and the spindle 22 insures the drive of the spindle at the same speed as the face plate from the 45 shaft 18, which is of course much slower than the speed of the pulley 12, by reason of the triple gear transmission. On the end of the spindle 22 is fixed a pinion 25 which meshes with a gear 26 compounded 50 with a pinion 27. The latter meshes with an idler 28 which in turn meshes with the gear 29 fast on the end of the feed screw 30 which is of common type.

In order to permit the speed of the drive 55 of the shaft 18 to be varied, the gear 17 is removable and may be substituted by a gear

of different size, and in this case the housing 31 in which gears 15 and 16 are supported, swings on the sleeve 13 to bring the pinion 16 into mesh with the new gear 17. The 60 parts are normally held in proper meshed relation by the clamping bolt 32 which works in the slots 33 of the brackets 34, 35. Similarly, if the speed of the feed is to be changed the idler 28 is changed 65 to the desired size and swung on its pivoted arm 36 to proper meshing relation to the pinions 27 and 29.

Each of the multiple face plates 21 is carried by an independent tail stock 37 having 70 V-grooves in its lower face to fit the ribs 38 on the lathe bed and along which the tail stocks are slideable to space the same apart the required distance to receive the blanks 39. Bolt plates 40 clamp the tail stocks in 75 adjusted position on the bed. Each face plate has a sleeve 41 journaled in a bearing in the head of the tail stock and held in position by a collar 42. The face plate center 43 is set into a recess in the face plate and 80 held in position by screws 44. It is centered with relation to the plate 21 by a short stud 45 which enters the bore of the sleeve 41. At the opposite end of the sleeve 41 is arranged a center 46 that corresponds to the 85 usual tail stock center. This center 46 is formed at the end of a rod 47 fitting the bore of the sleeve 41 and having a threaded section 48 which screws into the tapped end 49 of the sleeve. A knurled flange 50 is 90 formed on the rod adjacent the center 46 to afford a finger grip and the rod also carries a lock nut 51 in the form of a small hand wheel.

It is obvious that the center 46 which 95 serves as a tail stock center, and also the face plate center 43, are both driven at the same speed and revolve with the work blank. The face plate 21 and its related parts thus form a combined head and tail stock with 100 both centers rotatable.

The blank is engaged with the face plate through a dog 52 carried by the blank, and engaging slots 53 formed in the face plate to receive them and thus afford a driving connection for the blank. The tail center 46 is engaged with the blank by screwing the rod 47 out or in, by manipulation of the rod through the knurled flange 50, the lock nut 51 having been first loosened, whereupon the 110 latter is again tightened and the drive may be commenced.

The tool saddle comprises a pair of rails 54, 55, having V-grooves on their lower faces to engage and slide upon the ribs 56, 57, on opposite sides of the bed and outside the ribs 58 for the tail stock bed plate. In the upper faces of the rails are T-grooves 58 in which engage the guide ribs 59 of the cross pieces 60 of the tool posts 61 and also the heads of the securing bolts 62 by which the posts are fixed in adjusted position. Obviously the tool posts are longitudinally adjustable on the rails 54, 55, to proper position with relation to the tail stocks whereupon they having been secured, their tools act in unison simultaneously upon the several blanks. The cross pieces spanning the rails and bolted thereto connect the latter rigidly at five points and form a very rigid and substantial tool table.

20 The tool holder 63 is of common construction and preferably carries a pair of cutters 64, one arranged slightly in advance of the other so that the second tool serves only as the finishing tool and the wear thereon consequently much lessened. The feed apron 65 carried, with its appliances, by the front rail 54 of the tool table, is of common construction and operation and need not be explained in detail.

25 Among the advantages of the construction may be pointed out (1) capacity for acting on a large number of blanks simultaneously, (2) capacity for receiving a greater or less number of blanks according to the length of the latter, by removing or adding the combined tail stock and face plate units and their related parts, (3) flexibility of operation by adjusting either speed of drive or speed of tool feed, (4) simplicity 30 of combined head and tail stock unit constructions, (5) saving in wear through driving of both tail and head stock centers, (6) elimination of oiling troubles at ordinary stationary tail stock center, (7) improved head stock drive connections, (8) simple and rugged construction of tail stocks and tool table.

35 Various features of improvement will readily suggest themselves to those skilled 50 in the art without departing from what I claim as my invention.

I claim as my invention:—

1. A multiple lathe having a bed, a plurality of combined head and tail stocks arranged in tandem and longitudinally adjustable thereon, a tool table common to said organization, a plurality of tool carriers, one for each work blank, mounted on said table, and means for driving in unison the rotors of the several combined head and tail stocks and simultaneously traveling the tool table past the blanks to operate upon the series simultaneously.

2. In a multiple lathe, a combined head 65 and tail stock having a pair of oppositely

faced centers and means for driving the same simultaneously at the same speed.

3. In a multiple lathe, a combined head and tail stock having a pair of oppositely faced centers and means for driving the same simultaneously at the same speed, said centers being relatively displaceable to permit of the adjustment of a work blank without disturbing the position of the combined head and tail stock on the lathe bed. 75

4. In a multiple lathe, a combined head and tail stock having a pair of oppositely faced centers and means for driving the same simultaneously at the same speed, said centers being relatively displaceable to permit of the adjustment of a work blank without disturbing the position of the combined head and tail stock, together with means to lock the same in adjusted relation. 80

5. In a multiple lathe, a combined head and tail stock having a sleeved face plate, a center rigid therewith and an oppositely faced center adjustably secured to said sleeve. 85

6. In a multiple lathe, a combined head and tail stock having a sleeved face plate, a center rigid therewith and an oppositely faced center threaded to said sleeve. 90

7. In a multiple lathe, a combined head and tail stock having a sleeve face plate, a center rigid therewith and an oppositely faced center threaded to said sleeve, together with a lock nut for securing said center to the sleeve. 95

8. In a multiple lathe, a combined head and tail stock having a rotary face plate, oppositely faced live centers carried thereby, said plate having means for effecting a driving connection independent of the centers with a work blank. 100

9. In a multiple lathe, a plurality of rotary face plates, a shaft common thereto and operatively connected therewith, a driving rotor having a sleeve, gearing operatively connecting said sleeve and shaft, a spindle fast with one of the rotary face plates and passing through the sleeve of the driving rotor, a tool table feed screw and gearing operatively connecting said spindle with said feed screw, substantially as described. 115

10. In a multiple lathe, a lathe bed, ribs extending longitudinally on opposite sides thereof, a pair of rails slidably mounted thereon, a plurality of tool posts having bars spanning the bed and adjustably connected to said rails, substantially as described. 120

11. In a multiple lathe, a lathe bed, longitudinal ribs on opposite sides thereof, a pair of rails slidable on said ribs, and grooved on their upper faces, and tool posts having bases spanning the bed and adjustably secured in said grooves. 125

12. In a multiple lathe, a lathe bed having two pairs of longitudinal slideways thereon, a plurality of combined head and tail 130

stocks adjustably mounted on one pair of slideways and a tool table common to the several stocks, said tool table being mounted on the other pair of slideways, as de-
5 scribed.

13. In a multiple lathe, a series of combined head and tail stocks having their axes alined, said stocks being independently adjustable longitudinally of the lathe bed, and
10 means common to all of said stocks for driv-

ing their rotors synchronously, substantially as described.

In testimony whereof I have signed my name to this specification in the presence of two subscribing witnesses.

ABEL E. CHERNACK.
